MAGAZINE PENCIL

Original Filed Sept. 25, 1920

UNITED STATES PATENT OFFICE.

JOHN STRAKA, OF CHICAGO, ILLINOIS, ASSIGNOR, BY DIRECT AND MESNE ASSIGNMENTS, TO THE WAHL COMPANY, OF CHICAGO, ILLINOIS, A CORPORATION OF DELAWARE.

MAGAZINE PENCIL.

Application filed September 25, 1920, Serial No. 412,796. Renewed October 31, 1925.

This invention relates to magazine pencils and among its objects are to provide a simple, practical and comparatively inexpensive magazine pencil. Another object is to provide a magazine pencil having its handle or case arranged to contain the internal parts of a fountain pen. Another object is to provide novel means for feeding the lead out through the tip. Another object is to provide improved lead feeding means which may be readily attached to the handle or detached therefrom. Another object is to provide lead feeding mechanism which can be removed from the handle by a direct endwise movement and the feed pin thereof brought to loading position under the influence of gravity. Other objects and advantages will appear in the course of this specification and with all of said objects and advantages in view, this invention consists in the several novel features hereinafter fully set forth and more particularly defined in the claims.

The invention is clearly illustrated in the accompanying drawing, in which:

Fig. 1 is a side elevation of a magazine pencil, embodying a simple form of the present invention; Fig. 2 is a side elevation partly broken out to illustrate its inner construction; Fig. 3 is a side elevation of the pencil tip and an associated part; Fig. 4 is a side elevation of certain members of the pencil lead feeding means; Fig. 5 is a side elevation of a pencil lead feeding pin; Fig. 6 is a detail cross-section taken on the line 6--6 of Fig. 2 and Fig. 7 is a detail cross-section taken on the line 7--7 of Fig. 2. Figs. 2 to 7 inclusive, are upon a greatly enlarged scale, to more clearly illustrate the construction of the pencil.

Referring to said drawing, the reference character 10 designates a handle or case which may be in the form of a tube of ordinary length to form a convenient handle for the pencil. Said case or handle may be formed of hard rubber or other suitable material to give the pencil a pleasing and attractive appearance.

Within the case 10 is secured a tubular handle member 11 which, if desired, may extend the full length of the handle or case. In said tubular member 11 is a centrally apertured wall 12, which forms one end of the magazine 13, in which the lengths of lead are stored. For convenience in construc-

tion, said wall is fixedly secured in place by 55 a radially extending tongue 14, formed on the wall 12, which tongue enters a slot 15 formed in the wall of the tubular member 11. As a preference, I form said tube 11 out of a strip of flat material and form oppositely 60 disposed notches in its side edges, which when brought together, (when the strip is rolled up to form the tube) form the slot 15 for the reception of the tongue 14.

Centrally disposed in the magazine portion is a guide tube 16 for the lead feeding means. One end of said guide tube 16 is secured in the central aperture of the wall 12, as for instance by forcing it into the aperture, and the other end is likewise secured 65 in a strut or bar 17 which extends between the opposite walls of the inner tube 11 near its outer open end. The opposite side edges of the strut or bar 17 are curved as shown, and spaced away from the inner face of the inner 70 tube 11 to leave openings or passages 18 on opposite sides of the guide tube 16 through which the lengths of lead may be inserted 75 into the magazine and removed therefrom. It is to be understood that behind the strut 80 or bar 17 the magazine occupies the entire space around said guide tube 16, and that a large number of lengths of lead may be stored therein.

Removably secured at the open end of 85 magazine 13 is the conical tip 19 of the pencil, which may be formed of thin metal having a central opening 20 at its smaller end, and formed with a reduced shouldered portion 21 at its other end against which is secured a 90 centrally apertured end piece 22. The reduced portion 21 fits in the open end of the handle. A longitudinally slotted tube 23 is secured against rotation in the pencil tip 19 and said longitudinally slotted tube 23 projects beyond the end member 22 of the tip 95 and is adapted to extend into and be rotatively contained in the guide tube 16.

Movably contained in the slotted tube 23 is a tubular lead guiding member 24 which is 100 formed, throughout a portion of its length, with a helical slot 25 through which projects a head or bent end 26 of a lead feeding pin 27, which is contained in the bore or central hole 28 of the lead guiding member 24. The lead 105 feeding pin 27 and bore 28 are approximately of the same diameter as the diameter of the lead, enough clearance being left for the free

movement of the lead and pin. If desired, the outer end of the lead guiding member 24, that is to say the part which protrudes out through the small end of the tip 19, may be slit lengthwise as at 29 and the opposite walls of the tube may be bent slightly towards each other to form a slight pressure or grip on the lead to thereby prevent it from accidentally dropping out through the open end of the lead guiding member. On the opposite end of the lead guiding member 24 is secured a head or block 30 which is arranged to interlock with a block 31 fixedly secured against rotation at the inner end of the guide tube 16. The block 31 may be formed with a tongue 32 adapted to enter a notch or slot 33 formed in the outer end face of the block 30. This arrangement forms a sort of clutch mechanism between the spirally slotted lead guiding tube 23 and the handle for holding the lead guiding tube against rotation relative to the handle. The pencil tip, however, is free to turn in the open end of the handle and the lengthwise slotted tube 23 is free to turn with the tip, and as will be presently described, relative rotation between the tip and handle effectuates the feeding of the lead out through the end of the lead guiding member 24.

As illustrated in the drawing, the magazine 13 may be made comparatively short, but considerable space is afforded in said magazine around the guide tube 16 for the reception of leads. Said magazine may, however, be made to extend throughout the full length 35 of the handle if desired, but I have found that by providing a short magazine in the handle, the remainder thereof may be used to receive the reservoir 34, and other operative parts of a complete fountain pen construction 35, as is more fully set forth in a companion application filed on even date herewith and given the Serial No. 412,797. When the device is made to include the fountain pen construction, a removable cover 36 may be employed as is 45 customary, to cover the pen or nib of the fountain pen.

In operation, the handle and tip are rotated relatively, as for instance by taking hold of the tip with one hand and the handle with the other and giving one or the other a partial rotation in the proper direction, and the lead in the lead guiding member is thereby projected or fed out through the open end thereof. Assuming that the tip is held stationary and that the handle is rotated, it will be observed that the lead guiding member 24 is rotated through the instrumentality of its clutch connection with the handle, and that by reason of the engagement of the head or bent end 26 of the lead feeding pin 27 with the edges of the slot 28 of the slotted tube 23, which is held stationary with the tip, said pin is kept from rotating with the lead guiding tube, but because of the engagement of the 65 edge of the helical groove in said lead guiding

tube with the head of the pin the latter is moved longitudinally through the central bore of the lead guiding member, towards the open end thereof, thereby moving the length of lead in front of it out through the open end 70 of the lead guiding member.

When the length of lead has been used up, it may be replaced by a length taken from the magazine of the pencil. To replace the lead the tip is detached from the handle, thereby 75 uncovering the openings to the magazine. To detach the tip from the handle, it is pulled outward from the handle in a direct, endwise or lengthwise movement, which requires but an instant's time; the lead guiding member 24 is then withdrawn from the slotted tube 23, and when held in an upright position the lead feeding pin is free to gravitate to the lower end of the spiral slot. A length of 80 lead may then be inserted into the end of the lead guiding tube, the latter inserted into the slotted tube with the head of the pin entering the slit thereof and the tip replaced on the handle. When the parts are thus put together the clutch connection between the 85 spirally slotted lead guiding tube 24 and handle is reestablished, and by rotating the handle relative to the tip, in the proper direction, the lead is fed out through the open end of the lead guiding tube.

It is to be observed that the removable parts of the lead feeding mechanism may be disconnected by direct endwise movement, which requires but a moment's time, and that when the spirally slotted lead guiding tube and the member which prevents relative rotation between said helically slotted lead guiding tube and pin are disconnected by direct endwise movement, said lead feeding pin is free to gravitate along the spiral slot. 90

The parts are simple in construction and by reason of the peculiar arrangement of the lead feeding mechanism much less time is required to insert a new length of lead than in any of the magazine pencils now in common use.

It will be observed that by making the lead feeding mechanism disconnectable at the tip portion of the pencil, and by making the magazine comparatively short, the remainder of the handle may be utilized to contain the internal members of a fountain pen, thereby making the case serve as a handle for both the pencil and fountain pen.

More or less variation of the exact details of construction is possible without departing from the spirit of this invention; I desire, therefore, not to limit myself to the exact form of the construction shown and described, but intend, in the following claims, to point out all of the invention disclosed herein.

I claim as new, and desire to secure by Letters Patent:

1. A lead pencil, comprising a handle open at one end, a pencil tip removably and rota-

tively secured to the open end of said handle, a lengthwise slitted tube secured to said pencil tip and adapted to extend into said handle, a helically slotted lead guiding tube in said slitted tube, a clutch connection between said handle and helically slotted tube, and a lead feed pin slidable in said spirally slotted tube and having a head projecting out through the helical slot thereof and into the slit of the lengthwise slitted tube.

2. A lead pencil, comprising a handle open at one end, a centrally disposed guide tube fixedly secured in said handle, a pencil tip rotatively secured to the open end of said handle, a lengthwise slitted tube secured to said pencil tip and adapted to extend into said guide tube, a helically slotted lead guiding tube removably contained in said slitted tube, a clutch connection between said guide tube and helically slotted tube, and a lead feed pin slidable in said spirally slotted tube and having a head projecting out through the helical slot thereof and into the slit of the lengthwise slitted tube.

25 3. A lead pencil, comprising a handle open at one end, a centrally disposed guide tube fixedly secured in said handle, a pencil tip rotatively secured to the open end of said handle, a lengthwise slitted tube secured to said pencil tip and adapted to extend into said guide tube, a helically slotted lead guiding tube removably contained in said slitted tube, said helically slotted tube having a transversely slotted head at one end, a block secured in said guide tube and having a transverse tongue co-operating with said slotted head of the helically slotted tube to prevent relative rotation between said handle and helically slotted tube, and a lead feed pin 40 slidable in said helically slotted tube and having a head projecting out through the helical slot thereof and into the slit of the lengthwise slitted tube.

45 4. A lead pencil comprising a handle open at one end, a pencil tip rotatably and removably engaging the open end of said handle, a helical guide having a portion located within said tip, complementary clutch means carried by the handle and the helical guide respectively to normally prevent relative rotation of said handle and said guide, a lead propelling pin operable in and by said helical guide, and means for effecting relative rotation of said guide pin and said helical guide during relative rotation of said handle and said tip.

55 5. A lead pencil comprising a handle open at one end, a tip rotatably and removably engaging the open end of said handle, a helical guide having a portion located within said tip, clutch members carried by the handle and the helical guide respectively, one of said clutch members having a slot and the other a projection, so that when engaged they will prevent relative rotation of said handle and

said guide, a lead propelling pin operable in and by said helical guide, and means for effecting the rotation of said guide pin and said helical guide during rotative rotation of said handle and said tip.

6. A lead pencil comprising a handle open at one end, a tip rotatably and removably engaging the open end of said handle, a helical guide having a portion located within said tip, clutch members carried by the handle and the helical guide respectively, one of said clutch members having a transversely extending slot and the other having a transversely extending projection readily engageable in the slot, so that when engaged they will prevent relative rotation of said handle and said guide, a lead propelling pin operable in and by said helical guide, and means for effecting relative rotation of said guide pin and said helical guide during relative rotation of said handle and said tip.

7. A lead pencil comprising a hollow handle having an open end, a tip rotatably and removably mounted on the open end of the handle, a longitudinally slotted tube fixed to rotate with the tip, a lead-guide tube longitudinally movable in said slotted tube and formed with a spiral trackway, a propeller pin longitudinally movable in said lead-guide tube and having a portion engageable with the spiral trackway and a portion engageable with the slot in the longitudinally slotted tube, means in said handle for engaging with said lead-guide tube for causing these parts to rotate together upon rotation of the handle, said engaging means being detachable so that the tip, longitudinally slotted tube, lead-guide tube and propeller pin will be removable as a unit from the handle, and the lead-guide tube removed from the longitudinally slotted tube.

8. A lead pencil comprising a hollow handle open at one end, a tip rotatably and removably mounted on the open end of the handle, a slotted tube fixed to rotate with the tip, a lead-guide tube removably mounted in said slotted tube and formed with a spiral trackway, a propeller pin in said lead-guide tube and having portions engageable with said trackway and the slot of said slotted tube, and means in said handle for holding the handle and lead-guide tube fixed for rotation together when the lead-guide tube is inserted into the handle and to release the same when the lead-guide tube is withdrawn from the handle, the tip, slotted tube, lead-guide tube and pin being removable as a unit from the handle by a straight longitudinal pull upon the tip.

9. A lead pencil comprising a hollow handle open at one end, a tip rotatably and removably mounted on the open end of the handle, a longitudinally slotted tube, a lead-guide tube having a spiral trackway, a lead propelling pin engaging said trackway, both

of said tubes, said tip and said pin being removable as a unit from the handle by a straight longitudinal pull on the tip, said handle and one of said tubes having detachable interengaging parts for causing the last mentioned tube to rotate with the handle, the other tube being rotatable with the tip.

10. A lead pencil comprising a hollow handle open at one end, a tip rotatably and movably mounted on the open end of the handle, a tube fixed in said handle in spaced relation to the inner walls thereof to form a lead

magazine, a longitudinally slotted tube and a lead guide tube removably mounted in said first mentioned tube, a lead-propelling pin associated with the slotted tube and the lead-guide tube, the slotted tube, lead-guide tube, pin and tip being removable as a unit from the handle, and means associated with said first mentioned tube for detachably connecting the lead guide tube for rotation with the handle when the lead guide tube is inserted into the handle.

JOHN STRAKA.
